UNITED STATES PATENT OFFICE.

JAMES C. COVERT, OF WATERVLIET, NEW YORK.

SOLDERING-IRON.

SPECIFICATION forming part of Letters Patent No. 707,212, dated August 19, 1902.

Application filed April 14, 1902. Serial No. 102,919. (No model.)

To all whom it may concern:

Be it known that I, JAMES C. COVERT, a citizen of the United States, residing at Watervliet, in the county of Albany and State of New York, have invented certain new and useful Improvements in Soldering-Irons; and I do hereby declare the following to be a full, clear, and exact description of the invention, such as will enable others skilled in the art to which it appertains to make and use the same.

This invention relates to an improvement in soldering-irons, and it is embodied in the construction and arrangements of parts presently to be described, and defined in the claims.

The invention relates more particularly to that class of soldering-irons shown in United States Letters Patent No. 283,575, granted to myself on the 21st day of August, 1883. In said patent the forks or branches of the handle portion were cupped out on their inner adjacent faces, leaving a relatively narrow margin at the edges, and the soldering-iron was clamped between said margins by a suitable bolt. My present invention is designed as an improvement on such construction and is made to form a more positive connection between the iron and the holder or handle.

The present invention also relates to other features of construction presently to be described.

In the accompanying drawings, Figure 1 is an elevation showing the hand portion partly in section. Fig. 2 represents elevations, respectively, of the inner faces of the two forks or arms of the handle or stem. Fig. 3 is an enlarged side elevation showing parts broken away, and Fig. 4 is a cross-section taken on the line 4 4 of Fig. 3.

In soldering-irons it has been usual heretofore to construct the handle or holder portion of relatively hard metal, such as malleable iron or steel, and to clamp the same onto the relatively soft copper point, the pressure on the copper serving to break down any irregularities and form a close joint. I have found, however, that it is advantageous to have this connection between the holder and point more directly positive by causing the contacting surfaces to penetrate into the relatively soft metal of the point, thereby insuring a close while grasped contact between the two members, but permitting the movement of

one relative to the other when force is applied, and it is desirable to adjust the point to an angle. To accomplish this desired result, I 55 form the inner face of the arms B and B', which are carried by the stem A, with depressions C' and C' and arrange these depressions slightly eccentric to the ends of the fork, as shown in Fig. 2. By so arranging the depressions the margin or flange C is tapered gradually, forming thereby at the narrowest point a biting edge, which gradually increases in width to a point diagrammatically opposite its point. These cutting or biting edges 65 are arranged in opposite relation one to the other on the respective arms, so that the narrow portion of the right-hand arm will be opposite the broader portion of the flange of its companion or opposite arm for purposes presently to be stated. To form teeth or abutting shoulders at different points throughout the flange C, suitable cuts or depressions c' are made, conveniently in opposite sides and at the end of the arms, and owing to the tapered 75 formation of the flange one wall of the depressions will constitute a tooth of sufficient prominence or extension to bite into the metal of the point. Each of the end portions of the arms is provided with a central opening, and 80 on the arm B' is formed a raised boss D, surrounding the opening in the arm. This boss is conveniently formed with sloping sides, and its bore is threaded. This feature is in its nature an improvement on the construction 85 shown in my aforesaid patent in that a smooth surface is provided and an extended seat formed for the uniting-screw, which is designated at E. It has been found advantageous to have a smooth surface at the point of connection, so that in inserting the tool into and withdrawing it from a heater there will be no abrupt angles to form obstructions or interfere with the movement of the tool.

The point F is conveniently of copper and 95 is constructed with an ear or tongue F', of circular formation, having flat sides. The diameter of the ear or tongue is substantially that of the ends of the forked portion of the holder, its edge projecting slightly beyond, 100 as shown in Fig. 4. The flanges on the holder are so positioned relative to the tongue F' that their securing edges engage approximately the outer edge of the opposite faces of

the tongue, so that the tendency will be for the flanges to project slightly into the edges of the tongue. When the point is adjusted to proper position, the screw-bolt E is passed 5 through the aperture in one of the arms, through a central aperture in the tongue F', and finally into the screw-threaded aperture of the opposite arm and its boss. The parts are drawn tightly together by the screw-bolt, 10 causing the flanges to come in binding contact with the tongue of the point, and when it is desired to move the point to an angle it is only necessary to press the same, and in so doing the flanges on one side will tend to positively seat onto the metal of the point, while 15 on the other side the friction of the parts will assist in maintaining the required friction. Should the point be turned in an opposite direction, a similar result would follow, owing 20 to the opposite position or location of the retaining-flanges. The edges of the walls of the cross-grooves in the flanges serve as teeth, which take hold of the metal of the point slightly, and should the iron be adjusted repeatedly for any great length of time a well-defined seat is formed in the metal of the 25 point with which the slight edges or teeth will engage.

It has been found that the construction of 30 an iron as above described will form a very secure joint, and one wherein the point is firmly held against all movement either lateral or pivotal, and that by setting the screw-bolt the point can be moved and will be retained in its various positions of adjustment 35 without the necessity of tightening the bolt. Each time the point is adjusted the taper of the flanges causes them to readily enter the relative soft metal of the point and to thereby 40 increase the frictional engagement between the parts.

In construction I have found it desirable 45 to form the holder with a shank having longitudinal ribs throughout the length thereof and on the lower end have formed a series of teeth G, with inclined and transverse edges, the transverse shoulders or edges being presented upward or toward the point of the iron. By driving the handpiece H onto the shank 50 of the holder, a suitable opening having first been prepared, these teeth will serve to grasp the handpiece, which is conveniently of wood, and prevent the same from being detached.

Other forms of connection may, however, be made. 55

I am aware that modifications can be made without departing from the nature and principle of the invention.

Having thus described the invention, what I claim as new, and desire to secure by Letters Patent, is—

1. In a soldering-iron, the combination with a holder having separated arms at its ends each formed with penetrating edge flanges on its inner face, said flanges having cross-grooves therein and a boss formed on the outer face of one of the arms having a threaded interior, a point having a tongue fashioned to fit between the arms and be engaged by the flanges at or near the outer edge of the tongue, 65 and a screw-bolt passing through the arms and tongue having its end seated in the boss; substantially as described.

2. In a soldering-iron, the combination with a holder having separated arms at its end each 75 provided with engaging flanges having a series of cross-grooves the edges of the walls of which constitute teeth therein, a soldering-point having a flat-sided tongue, and means for securing the tongue between the flanges 80 of the arms, substantially as described.

3. In a soldering-iron, the combination with a holder having separated arms at its ends each formed with holding edge flanges on its inner face, and a boss formed on the outer 85 face of one of the arms having a threaded interior, a point having a tongue fashioned to fit between the arms and be engaged by the flanges at or near the outer edge of the tongue, and a screw-bolt passing through the arms 90 and tongue having its end seated in the boss, substantially as described.

4. In a soldering-iron, the combination with a holder having separated arms formed with holding-flanges and a pivot secured between 95 the flanges, of a handpiece into which the end of the shank of the holder fits, and a series of teeth on the opposite edges of the end of the shank having inclined outer and straight upper edges for engaging the handpiece. 100

In testimony whereof I affix my signature in presence of two witnesses.

JAMES C. COVERT.
